US0D1029878S

(12) **United States Design Patent** (10) Patent No.: **US D1,029,878 S**
(45) Date of Patent: ** Jun. 4, 2024

(54) **DISPLAY SCREEN OR PORTION THEREOF WITH GRAPHICAL USER INTERFACE**

(71) Applicant: **Gaeastar GmbH**, Berlin (DE)

(72) Inventors: **Maria Helena-Toscano Alvarez**, Berlin (DE); **Sanjeev Mankotia**, San Francisco, CA (US)

(73) Assignee: **Gaeastar GmbH**, Berlin (DE)

(**) Term: **15 Years**

(21) Appl. No.: **29/822,196**

(22) Filed: **Jan. 6, 2022**

(51) LOC (14) Cl. **14-04**

(52) U.S. Cl.

USPC **D14/489**

(58) **Field of Classification Search**

USPC D14/485-495

CLAIM

The ornamental design for a display screen or portion thereof with graphical user interface, as shown and described.

DESCRIPTION

The single view is a front view of a display screen or portion thereof with graphical user interface, showing our new design.

The dashed or broken lines in the FIGURE show a display screen or portion thereof, and form no part of the claimed design.

1 Claim, 1 Drawing Sheet
